(57) CLAIM

The ornamental design for an article holding clip, as shown and described.

DESCRIPTION

FIG. 1 is a perspective view of an article holding clip in full lines with an electronic device shown in broken lines representing environmental association matter being for illustrative purposes only and forming no part of the claimed invention.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof; and,

FIG. 7 is a bottom plan view thereof.
